UNITED STATES PATENT OFFICE.

WILLIAM PATRICK JOYCE, OF NEW ORLEANS, LOUISIANA.

ARITHMETICAL PRACTICING-CARDS.

1,323,986.

Specification of Letters Patent. Patented Dec. 2, 1919.

Application filed March 25, 1919. Serial No. 284,917.

To all whom it may concern:

Be it known that I, WILLIAM PATRICK JOYCE, a citizen of the United States, residing in New Orleans, in the parish of Orleans and State of Louisiana, have invented certain new and useful Improvements in Arithmetical Practicing-Cards, of which the following is a specification.

The object of this invention is to provide means for so training the mind as to enable one to add numbers, columns of figures, etc., with accuracy and with great celerity.

For this purpose I provide a pack of cards which are consecutively numbered, each card except the first bearing also a number representing the sum of the consecutive number of that card and the consecutive numbers of all of the preceding cards in the series. Any desired number of cards may be employed, say one hundred, and the consecutive numbers may be arranged in the center of the cards, while the numbers indicating the sum of the consecutive numbers may be arranged in the corners of the cards. By turning to any card in the series the desired information as to the sum of the consecutive number on that card and the consecutive numbers of all of the preceding cards may be readily ascertained, but primarily the cards are intended as a means for training the mind to quickly and accurately add numbers of any kind without resorting to the slow methods commonly used.

Experience has demonstrated that after the training afforded by the use of my cards, long columns of figures can be added as fast as recorded with the greatest facility; in fact, the sum or total of the figures may be known and recorded immediately after the last figures of the column have been written.

In the accompanying drawings:—

Figure 1 is a perspective view of a pack of arithmetical practice cards made in accordance with my invention.

Fig. 2 shows a series of the cards and indicates how the consecutive numbers and the sum numbers are printed thereon.

Fig. 3 is a view of the front of the first card in the series on which the consecutive number 1 is printed.

Fig. 4 is a view of the reverse side of this card on which the number 101 is printed.

Fig. 5 is a view of the front of the 75th card in the series on which the consecutive

number 75 is printed and the sum number 55 2850 is also printed.

Fig. 6 is a view of the reverse side of the 75th card.

Fig. 7 indicates a column of figures with the sum or total of these figures when added.

In using the cards for mental training the pupil is taught to glance at a series of cards in regular order, and as he proceeds to mentally add the consecutive numbers, and at first as the addition proceeds, noting the sum of these numbers indicated on the last card examined, but afterward performing the operation without examining the sum numbers. After he has become proficient in adding simple numbers in this way, he is allowed to use a greater number of cards and to proceed with them until he becomes proficient in the use of these cards also. This method is continued until the mind or brain is so trained or developed that the pupil can quickly add any consecutive number of cards in series. After this, the cards may be shuffled and the pupil trained to add mentally and without making a record any numbers indicated on the cards. He may then be trained to deal with still larger numbers, arbitrarily selected and not necessarily indicated on the cards until finally by constant or methodical practice the brain of the pupil is so trained that he can quickly add any numbers as fast as indicated or recorded.

This training when once perfected is practically permanent, but the mental condition which gives facility in adding is best retained by from time to time practicing with the cards.

It will be observed that the cards on their front faces are numbered consecutively from 1 to 100 and that each card contains a sum number. Where the pupil goes through the whole pack of cards, adding as he proceeds, card number 1 will then be on the bottom of the pack and card 100 on the top of the pack. I prefer to print on the backs of the cards in the pack consecutive numbers from 101 to 200 so that the pupil can, while arranging the cards in proper numerical order from 1 to 100, deal with cards arranged in regular order or series from 101 to 200, so that when he gets to the two-hundredth card by reversing the pack he will have a pack of cards numbered consecutively from 1 to 100 as before. If the pupil is a beginner in the

training he should be taught not to attempt to add the three figures of each consecutive number, but to only use the first and second figures. Afterward he may practice with 5 three figures in the manner before described.

Figs. 3 and 4 of the drawings show the front and rear sides of the card A, which is the first card in the pack. Figs. 5 and 6 show the front and rear sides of the seventy- 10 fifth card B in the series, and it will be observed that on the back of the seventy-fifth card the number 175 is printed, and the same rule is followed in the series of cards. On the back of card number 1 the number 101 15 is printed as shown in Fig. 4. On the back of card number 12, for instance, the number 112 is printed.

Fig. 7 of the drawing shows a column of figures in which there are four digits in each 20 horizontal line. In adding such a column, one trained in the manner hereinbefore described can start at the top and quickly pass from one number to the next, adding the whole of that number to the whole of 25 the next number, and so on to the bottom and then immediately record the total, it not being necessary as is commonly the case to add one vertical row of figures, record this sum, then the next row, and 30 so on.

It will be understood that the cards are not used to assist in adding figures or columns of figures, but are employed to train the mind of the pupil who uses them for 35 practice purposes to obtain facility and accuracy so that he may, whenever occasion requires, add numbers or columns of figures, either large or small, as it were intuitively, or certainly so quickly or with 40 such ease as to seemingly be intuitive.

The sum numbers of the cards are serviceable especially for beginners, for instance in verifying the additions when practicing with simple numbers, and a simple arrangement of cards.

It will be observed that in my system, numbers are dealt with extending beyond the number 9. In ordinary addition single numbers (from 1 to 9) are added when adding up a column of figures, whereas in my 50 system the pupil is trained to deal with a

plurality of numbers in each line of digits. For instance, he will add the number 26 to the number 55 by one operation instead of first recording 6 and then 5 and saying 11, 55 carrying 1, adding 1 to 5, saying 6, then adding 2 to 6 and saying 81, he will add the numbers 26 and 55 simultaneously, obtaining 60 81 by one operation. The same rule is followed with three numbers, the pupil being taught after having practiced with smaller numbers to add three numbers simultaneously. I preferably, however, use in my system one hundred cards, consecutively numbered, in the manner before explained, as 65 these cards are sufficient for the mental training which will give facility in adding numbers of any kind. The manipulation of the cards assists materially in the training, especially with beginners.

The sum number on each card serves as a record to show the total of the cards examined when one has gone part way through the pack and is for any reason interrupted or delayed.

70 I claim as my invention:

1. A series of cards for practicing addition which have printed on their front faces numbers arranged consecutively in regular order from first to last and each of which except the first has printed on its front face, in addition to its consecutive number a number indicating the sum of the consecutive number thereon and the consecutive numbers on all the preceding cards in the 85 series.

2. A series of cards for practicing addition which have printed on their front faces numbers arranged consecutively in regular order from first to last and each of which except the first has printed on its front face, in addition to its consecutive number a number indicating the sum of the consecutive number thereon and the consecutive numbers on all the preceding cards in the 90 series, and each of said cards having printed on its back another separate number which is one of a different series of numbers starting 95 from the first card of the first series.

In testimony whereof, I have hereunto 100 subscribed my name.

WILLIAM PATRICK JOYCE.
